CLAIM

The ornamental design for a heat sink, as shown and described.

DESCRIPTION

FIG. 1 is a perspective view of the top of a heat sink showing my new design;

FIG. 2 is a perspective view of the bottom of the heat sink of FIG. 1;

FIG. 3 is a top plan view thereof;

FIG. 4 is a bottom plan view thereof;

FIG. 5 is a front elevational view thereof, the rear view being a mirror image;

FIG. 6 is a right side elevational view thereof, the opposite side being a mirror image;

FIG. 7 is a cross-sectional view thereof taken along line 7—7 of FIG. 3;

FIG. 8 is an enlarged top fragment view of the pin and pin base taken of the circled area of FIG. 3; and,

FIG. 9 is an enlarged elevational fragment view of the pin and pin base taken of the circled area of FIG. 7, the rear and side elevational views being the same.

FIG. 1

FIG. 2

FIG. 3

FIG. 4

FIG. 5

FIG. 6

FIG. 7

FIG. 8

FIG. 9
